US0D1080599S

(12) **United States Design Patent** (10) **Patent No.:** **US D1,080,599 S**
(45) **Date of Patent:** **** Jun. 24, 2025**

(54) **MOBILE PHONE CASE**

(71) Applicant: **Qiankai Zheng**, Guangzhou (CN)

(72) Inventor: **Qiankai Zheng**, Guangzhou (CN)

(**) Term: **15 Years**

(21) Appl. No.: **29/995,230**

(22) Filed: **Mar. 25, 2025**

(51) LOC (15) Cl. **03-01**

(52) U.S. Cl.

USPC **D14/250**; D3/218; D14/253

(57) **CLAIM**

The ornamental design for a mobile phone case, as shown and described.

DESCRIPTION

FIG. 1 is a top, front, right side perspective view of a mobile phone case, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a top, rear, left side perspective view showing the mobile phone case with its support stand in an extended state.

The evenly dotted broken lines illustrate portions of the mobile phone case and form no part of the claimed design.

1 Claim, 9 Drawing Sheets
